UNITED STATES PATENT OFFICE

ZIGMAN CHAPLICK, OF CHICAGO, ILLINOIS

DESIGN FOR AN ASH RECEIVER

Application filed March 21, 1931. Serial No. 39,195. Term of patent 7 years.

To all whom it may concern:

Be it known that I, ZIGMAN CHAPLICK, a citizen of the United States, residing at 732 Mather Street, Chicago, Illinois, have invented a new, original, and ornamental Design for an Ash Receiver, of which the following is a specification, reference being had to the accompanying drawings, forming part thereof.

In the drawings:
Fig. 1 is a plan view,
Fig. 2 is a front elevational view, and
Fig. 3 is a sectional view of the base along line 3—3 of Fig. 2.

I claim:
The ornamental design for an ash receiver as shown.

ZIGMAN CHAPLICK.
